CLAIM

The ornamental design for a nozzle for water purifier as shown and described.

DESCRIPTION

1. Nozzle for water purifier

1.1 : Perspective

1.2 : Front

1.3 : Left

1.4 : Top

1.5 : Bottom

1.6 : Cross sectional

1.7 : Reference

1.8 : Reference

The omitted rear view is a mirror image of the front view; the omitted right view is a mirror image of the left view; reproduction 1.6 is a vertical cross-sectional view of reproduction 1.4; reproduction 1.7 shows a state of use with its adjustable length; reproduction 1.8 shows another state of use wherein broken lines depict environmental structure and form no part of the claimed design.
